UNITED STATES PATENT OFFICE.

REINHARDT NESSLER, OF EAST OAKLAND, CALIFORNIA.

EXPLOSIVE-ENGINE.

No. 923,069.

Specification of Letters Patent.

Patented May 25, 1909.

Application filed August 17, 1908. Serial No. 448,914.

To all whom it may concern:

Be it known that I, REINHARDT NESSLER, a citizen of the United States, residing at East Oakland, in the county of Alameda 5 and State of California, have invented a new and useful Improvement in Explosive-Engines, of which the following is a specification.

This invention is an improvement upon 10 two cycle engines in which the crank chamber is employed as a compression chamber, and the object of the invention is to secure a more economical use of the explosive gases by compressing them in the explosion chamber by means of a peculiar construction of 15 the piston and a special arrangement of the ports.

The invention consists in the novel features of construction hereinafter described, 20 pointed out in the claims and shown in the accompanying drawings, in which:

Figure 1 is a vertical section through the engine. Fig. 2 is a vertical section taken at right angles to Fig. 1. 25 In these drawings 1 represents an upright cylinder provided through its upper half, in which the explosion chamber is located, with a water jacket 2, and surrounded through its lower half by a gas and air receiver 3. A

30 pipe 4 leads from the carbureter, not shown, to said receiver, the pipe being provided with a valve casing 5 in which is the usual form of spring pressed check valve. The cylinder 1 rests upon a suitable base 6 which 35 also forms a housing for the cranked portion 6^a of a drive shaft, to said crank portion a pitman 7 being connected. At its upper end this pitman is pivoted within a cylindrical, downwardly open piston 8 which 40 works in the lower portion of the cylinder 1 which portion is of a diameter slightly less than the remainder of the cylinder. Where the diameter of the cylinder changes 45 an offset is formed which will be referred to hereafter, and which offset is substantially in a horizontal plane with the upper portion of the piston 8 when the latter is in its lowest position, as shown in the drawings. The piston 8 carries a dome 9 which extends 50 into a second cylindrical piston 10, having a non-perforate top, and the two pistons are connected together by a web 11 secured to the dome 9. The above construction forms a compound piston and there is no direct 55 communication between the interior of the piston 10 and the exterior air. Ports 12 are

formed in the offset portion above referred to and afford communication between the receiving chamber 3 and the interior of the piston 10. A slot 13 in the piston 10 communicates, when the piston is in its lowest position with a by-pass 14 which leads into the top of the cylinder 1, the upper end of said by-pass being controlled by a spring 60 pressed check valve 15. A spark plug 16 extends into the upper end of the cylinder 1, and an exhaust port 17 is formed in one side of said cylinder, said port being at the lower limit of the explosion chamber.

The operation of the engine is as follows:—As the piston 10 moves upward it acts 70 as a suction plunger and, drawing mixed air and gas from the carbureter through the pipe 4, fills the receiver 3 and also the interior of the piston 10, and upon the down 75 stroke this charge is compressed. At the completion of the down stroke the slot, or port, 13 registers with the by-pass 14 and the compressed charge enters the explosion chamber formed by the upper part of the 80 cylinder, where it is again compressed on the second upstroke of the piston, and is then exploded and acts against the piston driving it on its down stroke, and upon the end of this down stroke a new charge will 85 enter by way of the by-pass and will drive out the products of combustion remaining from the previous explosion, through the exhaust port 17, and will be in turn compressed on the next upstroke and then exploded. This operation will be continued 90 during running of the engine.

What I claim is:

1. An engine of the kind described comprising a cylinder having an offset portion 95 having ports therein, an air and gas receiver inclosing said offset portion, a hollow piston open adjacent one end and slotted on one side, a by-pass communicating with said slot when the piston is at the end of a down stroke, said by-pass opening into the upper end of the cylinder, and means for admitting an explosive mixture into the receiver, the ports of the offset portion admitting the mixture from the receiver to the piston. 100

2. In an engine of the kind described, a cylinder, the lower portion of said cylinder being reduced in diameter, an explosive mixture receiver surrounding said reduced portion, a piston sliding in said portion, a dome 110 carried by the piston, a second piston inclosing said dome and open around the end

which said dome enters, the cylinder having ports affording communication between the receiver and the interior of said second piston, a by-pass leading from the side of the cylinder to the upper end of the cylinder and a spark plug extending into said end, the second piston being slotted to register with the by-pass at the end of each alternate stroke.

10 3. In a gas engine, an engine cylinder having laterally opening inlet ports and an exhaust port, a by-pass leading from the side of the cylinder to the explosion end, and a

compound piston working in said cylinder, said piston comprising upper and lower 15 downwardly open cylinders, the lower cylinder having a dome extending into the upper one, the upper cylinder receiving an explosive charge through said inlet ports, and having a slot registering with the by-pass at 20 the end of each alternate stroke of said piston.

REINHARDT NESSLER.
